WALKING HOBBYHORSE

Edward P. O'Donnell, Oklahoma City, Okla., assignor to B. F. Kelley, Tulsa, Okla.

Application October 10, 1936, Serial No. 105,128

9 Claims. (Cl. 272—53)

This invention relates to toys and more particularly to an animated toy or walking hobby horse.

The object of the invention is to provide a toy horse of simple and inexpensive construction which may be safely used by children in the same manner as a hobby horse and which will automatically walk or progress in a forward direction with a step by step movement as the weight of the rider is alternately shifted from the saddle to the stirrups.

A further object of the invention is to provide an animated toy comprising pivotally connected front and rear sections fashioned in simulation of a horse and normally and yieldably supported with a portion of adjacent faces disposed at an angle to each other whereby when the weight of the rider is imposed upon the saddle, the angular faces of the sections will contact and allow forward movement of the front legs of the horse, and when the weight of the rider is transferred to the stirrups, said angular faces will separate and permit a corresponding forward movement of the rear legs of the horse.

A further object is to provide a stirrup actuated member pivotally mounted on one section and having a flexible connection with the other for moving the lower ends of said sections together when the weight of the rider is imposed on the stirrups.

A still further object of the invention is generally to improve this class of devices so as to increase their utility, durability, and efficiency.

In the accompanying drawings forming a part of this specification and in which similar numerals of reference indicate corresponding parts in all the figures of the drawings,

Figure 1 is a side elevation of a walking hobby horse embodying the present invention.

Figure 2 is a similar view, partly in section, and showing in dotted lines the position assumed by the front and rear legs of the hobby horse when the weight of the rider is imposed on the saddle.

Figure 3 is an enlarged vertical sectional view showing the pivoted sections depressed under the weight of the rider and ready to be returned to normal position by the stirrup actuating member.

Figure 4 is a vertical transverse sectional view taken on the line 4—4 of Figure 2 and looking in the direction of the arrows.

Figure 5 is a perspective view of the stirrup actuating member and its associated parts detached.

The toy forming the subject-matter of the present invention comprises a body portion 5 fash-

ioned in simulation of any well-known animal, preferably a horse, and including front and rear sections 6 and 7 provided with front and rear legs 8 and 9, respectively, as best shown in Figure 1 of the drawings. The inner portions of the sections 6 and 7 are pivotally united by a hinge joint 10 disposed at approximately the center of the body portion, the adjacent faces of the sections immediately below the pivot pin being disposed parallel with each other, as indicated at 11, and the adjacent faces of the sections above the pivot being arranged at an angle to each other, as indicated at 12, so as to permit the inner ends of said sections to be alternately depressed and elevated, as will be more fully described hereinafter. 15 The sections comprising the body portion are preferably hollow to form an interior chamber 13, and disposed within said chamber is a coil spring 14, one end of which is anchored to a pin 15 on the rear section and the other end anchored to a corresponding pin 16 on the front section of the body portion so as to normally and yieldably hold the parallel faces 11 of the sections in contact with each other and assist in returning the sections to normal position after they have been separated by the weight of the rider. Pivotally mounted, at 17, on the forward section 6 is a saddle 18 and the rear end of the saddle rests loosely on the rear section 7 of the horse so as to permit movement of said section without disturbing the position of said saddle. 20

The lower extremities of the front and rear legs of the toy horse are provided with openings 19 through which extend stub shafts 20 provided with traction wheels 21 and 22 preferably equipped with rubber tires so as not to mar the floor or other surface over which the horse travels. Secured to the axles of the front and rear legs are ratchet wheels 23 and pivotally mounted between the legs and coacting with the teeth on the ratchet wheels are U-shaped pivoted pawls 24, the purpose of which is to allow movement of the legs in one direction only. Surrounding each stub shaft 20 and interposed between the traction wheels and adjacent legs of the horse are spacing sleeves 25, certain of which move with the stub shaft and others being loosely mounted thereon. The traction wheels 22 are keyed to the stub shafts 20, while the traction wheels 21 are free to revolve thereon so as to permit the horse to make turns or travel in a curved path, if desired. 45

Pivotally mounted, at 26, on the forward section of the body portion is a stirrup actuating member 27 having its pivoted end provided with 50

a cam face 28 and its free end formed with a lever 29, the end of which is reduced to provide a tongue 30 which fits between spaced ears 31 of a depending bar 32, there being a pivot pin 5 33 extending through the tongue and ears 31 and forming a pivotal connection between the parts, as best shown in Figure 5 of the drawings. The lower end of the depending bar is bifurcated, at 34, to receive a cross bar 35 to which it is pivoted, 10 at 36. The opposite ends of the cross bar 35 are formed with slots 37 adapted to receive suspension straps 38 carrying stirrups 39, one of which is disposed at each side of the hobby horse, as shown.

15 Connecting the bar 27 and cam 28 and preferably formed integral therewith is a reinforcing web 40 having an opening therein through which extends one end of a chain or other flexible element 41, the opposite end of which is secured to 20 a pin 42 carried by the rear section of the body portion so that when a downward pressure is exerted on the stirrups 39, the cam 28 will exert a longitudinal pull on the chain 41 and draw the sections together.

25 Assuming the parts to be in the position shown in full lines in Figure 2 of the drawings, the weight of a child on the saddle 18 will depress the pivoted ends of the front and rear sections to the position shown in Figure 3 of the drawings. As 30 the sections are depressed, the pawl 24 on the rear section will prevent rearward movement of the rear legs of the horse, while the pawl 24 on the front section will permit the front legs to be moved forwardly in a direct line to the dotted line position shown in Figure 2. When the 35 weight of the rider is shifted from the saddle to the stirrups 39, the lever of the actuating member 27 will be forced downwardly, thereby exerting a pull on the chain 41 and bringing the lower portions of the sections together to the position shown in full lines in Figure 2 of the drawings. When the saddle is depressed, the spring 14 will expand so that when the weight of the rider is shifted to the stirrups, the spring 14 40 will assist in returning the sections to normal position.

It will thus be seen that as the rider alternately shifts his weight from the saddle to the stirrups, the horse will be caused to travel or progress in a forward direction with a step by step movement, which forward movement of the horse will continue as long as the rider shifts his weight from the saddle to the stirrups.

Detachably secured to the forward section 6 45 by screws or similar fastening devices 43 are removable side plates 44, preferably painted to represent a saddle blanket, and which act as side closures and guides for the body sections when depressing and elevating the same. The saddle 50 18 is preferably provided with a flexible skirt 45 which overhangs the side plates and assists in preventing the entrance of dust and dirt between the body sections.

A toy horse constructed in accordance with 55 the present invention will not only afford a child the same amusement and diversion incident to riding an ordinary hobby horse, but, in addition thereto, will also simulate the movements of a live horse in the act of walking and provide a 60 mild, healthy exercise for the rider.

It will, of course, be understood that the toy horses may be made in different sizes and shapes and painted or otherwise ornamented to give them the appearance of a live animal without departing from the spirit of the invention.

Having thus described the invention, what is claimed as new is:

1. A hobby horse comprising a body portion including pivotally united front and rear sections having leg portions, means for yieldably supporting the adjacent faces of the sections in contact with each other, a saddle spanning the junction of said sections and adapted to be depressed by the weight of a rider for separating the lower portions of the sections to permit forward movement of the front legs of the horse, stirrups depending from the front section, an actuating member operatively connected with the stirrups, and a flexible connection between the actuating member and said rear section for moving the lower portions of the sections together and advancing the rear legs of the horse when the weight of the rider is transferred to the stirrups.

2. A hobby horse comprising a body portion including pivotally united front and rear sections having depending leg portions, stub shafts extending through the leg portions and provided with traction wheels, ratchet wheels carried by the stub shafts, pawls mounted on the leg portions and engaging the ratchet wheels, a saddle spanning the pivotal junction of said sections and adapted to depress the sections when the weight of the rider is imposed on the saddle, an actuating member carried by the forward section 20 and operatively connected with the rear section, and stirrups depending from the actuating member for causing said actuating member to move the pivoted sections to elevated position when the weight of the rider is transferred from the saddle 25 to said stirrups.

3. A hobby horse comprising a body portion including pivotally united front and rear depressible sections having leg portions, a saddle pivotally mounted on one section and loosely 40 contacting the other section, said saddle being actuated by the weight of a rider thereon to depress the sections, an actuating member pivotally mounted on the forward section and provided with a cam surface, a flexible element 45 secured to the actuating member and extending over the cam surface for engagement with the rear section, and stirrups operatively connected with the actuating member and adapted to elevate said sections when the weight of the 50 rider is transferred from the saddle to the stirrups.

4. A hobby horse comprising a body portion including pivotally united depressible sections having leg portions, traction wheels carried by 55 the leg portions, pawl and ratchet mechanism operatively connected with the traction wheels, a spring forming a yieldable connection between the pivoted ends of the sections, a saddle spanning the junction of the sections and adapted to depress said sections when the weight of the rider is imposed thereon, an actuating member pivotally mounted on the forward section and having its pivoted end provided with a cam surface and a longitudinally disposed bar, a vertical bar pivotally connected with the longitudinal bar, a cross bar connected with the vertical bar, a web uniting the cam surface and longitudinal bar, a flexible element having one end thereof secured to the web and its other end extending over the cam surface and connected with the rear section, and stirrups depending from the cross bar for moving the actuating member to elevate the pivoted sections when the weight of 70 75 80 85 90 95 100 105 110 115 120 125 130 135 140 145 150 155 160 165 170 175 180 185 190 195 200 205 210 215 220 225 230 235 240 245 250 255 260 the rider is transferred from the saddle to the stirrups.

5. A hobby horse comprising a body portion including pivotally united front and rear hollow 5 depressible sections defining an interior chamber, a spring disposed within said chamber and forming a yieldable connection between the sections, a saddle pivotally mounted on one section and slidably engaging the other section and 10 adapted to depress both sections when the weight of the rider is imposed on the saddle, an actuating member pivotally mounted within the chamber and provided with a cam surface terminating in a longitudinal bar, a flexible element 15 connected with the actuating member and extending over the cam surface for engagement with the rear section, and stirrups depending from the bar for tilting the actuating member to elevate the sections when the weight of the 20 rider is shifted from the saddle to said stirrups.

6. A hobby horse comprising a body portion including pivotally united front and rear depressible sections, means forming a yieldable connection between the pivoted ends of said sections, a saddle spanning the pivotal junction of the sections and adapted to depress the same when the weight of the rider is imposed thereon, an actuating member pivotally mounted on the front section and having its pivoted end provided with a cam surface and a longitudinal bar terminating in a reduced tongue, a perforated reinforcing web connecting the bar and cam surface, a vertical suspension bar having its upper end provided with ears receiving the tongue and 30 to which it is pivotally connected and its lower end bifurcated, a cross bar pivotally mounted in the lower end of the suspension bar and provided with terminal openings, straps fitted in said openings, a chain having one end thereof 35 fitted within the opening in the web and its other end extending over the cam surface and secured to the rear section, and stirrups carried by the straps for tilting the actuating member to elevate the pivoted sections when the weight of the 40 rider is transferred from the saddle to said stirrups.

7. A hobby horse comprising a body portion including pivotally united depressible front and

rear sections provided with leg portions, yieldable means connecting said sections, a saddle spanning the pivotal junction of the sections, stirrups depending from the forward section, and means operable by alternately transferring the 5 weight of a rider from the saddle to the stirrups, respectively, for advancing the legs in a forward direction with a step by step movement.

8. A hobby horse comprising a body portion including pivotally united front and rear depressible sections having leg portions, the opposing faces of the sections on one side of the pivot being disposed parallel with each other and the opposing faces on the other side of the pivot being disposed at an angle to each other 15 to form a V-shaped recess, yieldable means uniting the pivoted ends of the sections, side plates detachably secured to the forward section and slidably overlapping the rear section and serving to close said V-shaped recess, a saddle pivotally 20 mounted on the forward section and provided with a skirt overhanging the side plates, stirrups depending from the forward section, and means operable by alternately transferring the 25 weight of a rider from the saddle to the stirrups, respectively, for advancing the legs in a forward direction with a step by step movement.

9. A hobby horse comprising a body portion including pivotally united front and rear sections having leg portions and each provided at its inner end with a pair of flat faces at an angle to each other and converging toward the opposite section, a spring forming a yieldable connection between the pivoted ends of the sections, a saddle spanning the junction of said sections and 30 adapted to be depressed by the weight of the rider for bringing two of the adjacent faces of the sections together to permit forward movement of the front legs of the horse, stirrups depending from the front section, an actuating 35 member operatively connected with the stirrups, and a flexible connection between the actuating member and said rear section for moving the other adjacent faces of the sections together and advancing the rear legs of the horse when the 40 weight of the rider is transferred to the stirrups. 45

EDWARD P. O'DONNELL.
